ARCH SUPPORT

Herman A. Holscher, Galesburg, Ill., assignor of
one-third to Louis L. Goode and one-third to
Craig L. Brown, both of Galesburg, Ill.

Application December 28, 1936, Serial No. 117,955

2 Claims. (Cl. 36—71)

This invention relates to what is commonly known as an "arch support", and particularly has reference to a "shell" that may be formed over a last and suitably padded or handled by the chiropodist as the individual case demands.

An object of my invention is the construction of a flexible foot support which will admirably fit the foot of the wearer and thereby greatly strengthen the foot, as well as affording easy walking.

Another object of my invention is the construction of an all foot support which incorporates, in a single flexible unitary structure, the unique and novel features whereby the entire foot is strengthened, tending in time to result in a permanent cure for any deformities, and which support will admirably fit the ordinary shoe of the wearer.

With the foregoing and other objects in view, my invention comprises certain novel constructions, combinations and arrangements of parts or units as will be hereinafter fully described, illustrated in the accompanying drawings and more particularly pointed out in the appended claims.

In the drawing:

Figure 1 is a top plan view of a device constructed in accordance with the present invention.

Figure 2 is a sectional view taken on line 2—2 of Figure 1, and looking in the direction of the arrows.

Figure 3 is a sectional view taken on line 3—3 of Figure 1, and looking in the direction of the arrows.

Figure 4 is a sectional view taken on line 4—4 of Figure 2, and looking in the direction of the arrows.

Figure 5 is a perspective view of the device, partly shown in section.

Referring to the drawing by numerals, 1 designates the elongated body of the device, which body is flexible throughout its entire length and preferably formed of leather, although other suitable material may be employed in the construction of said body. The body 1 is provided with an integral outer side flange 2, a rear or heel flange 3, an inner side flange 4, and a toe flange 5.

The heel flange 3 with the rear portions of side flanges 2 and 4 constitute a cupped heel, which locks the calcaneus bone and eliminates creeping of support. The height of the flanges,

constituting the cup, may vary from one-thirty-second of an inch to two inches, as the constructor desires.

The forward end of the body 1 is provided with a large flat substantially oval ball-of-foot receiving portion 6, extending diagonally across the longitudinal axis of the elongated body 1, to conform to the shape of the "ball" of the foot. This novel construction admirably receives the ball of the foot in its proper position, with the toe flange 5 supporting and strengthening the toes, while the troughs 7 and 8 fit snugly around outer portions of the big toe and little toe as clearly indicated by the dotted lines of the foot shown in Figures 1 and 2.

A light suede covering 9 is suitably fastened to the planter or bottom side of body 1.

In constructing my device I may use a regular shoe last, and fit the device exactly to the length and width shoe worn by the patient. Further, the chiropodist may take my novel device and pad or add to the same, to meet such conditions of a patient's foot, as will further assist in relieving the patient or perfecting a cure.

While I have described the preferred embodiment of my invention and illustrated the same in the accompanying drawing, certain minor changes or alterations may appear to one skilled in the art to which this invention relates during the extensive manufacture of the same and I, therefore, reserve the right to make such alterations or changes as shall fairly fall within the scope of the appended claims.

What I claim is:

1. As a new article of manufacture, a foot support comprising an elongated flexible body provided with a circumferential upstanding flange entirely around its edge, said flange at the toe end of said body provided with toe-receiving troughs, and said body also provided at the inner end of said troughs and toe flange with a large flat substantially oval portion extending diagonally across the longitudinal axis of said body.

2. A foot support formed from a single piece of flexible material and being provided at its front end with an upstanding toe flange, said toe flange slightly grooved in opposite directions to provide troughs for snugly fitting the big and little toe of a foot, and an oval flat portion on said support extending across the entire toe flange at its base.

HERMAN A. HOLSCHER.
